(57) **CLAIM**

The ornamental design for an adjustable clamp device, as shown and described.

DESCRIPTION

FIG. 1 is a perspective view of the top of an adjustable clamp.

FIG. 2 is a perspective view of the top of the adjustable clamp.

FIG. 3 is a perspective view of the bottom of the adjustable clamp.

FIG. 4 is a side view of the adjustable clamp.

FIG. 5 is a top view of the adjustable clamp.

FIG. 6 is a bottom view of the adjustable clamp.

FIG. 7 is a side view of the adjustable clamp; and,

FIG. 8 is a side view of the adjustable clamp.

The drawings contain a symbolic break. The break lines, as well as the area between the break lines, form no part of the claimed design.

1 Claim, 7 Drawing Sheets
